United States Patent Office

Des. 190,870
Patented July 11, 1961

190,870

CULTIVATING HOE

Oliver H. Blankenship, Highway 60, P.O. Box 234,
Poplar Bluff, Mo.

Filed Oct. 26, 1959, Ser. No. 58,056

Term of patent 14 years

(Cl. D39—1)

I claim:

The ornamental design for a cultivating hoe, as shown and described.
